FERDINAND M. HOLMES, OF EVERETT, MASSACHUSETTS.

BOOKKEEPING-MACHINE.

1,254,907.

Specification of Letters Patent. Patented Jan. 29, 1918.

Application filed May 4, 1917. Serial No. 166,468.

To all whom it may concern:

Be it known that I, FERDINAND M. HOLMES, citizen of the United States, residing at Everett, in the county of Middlesex and State of Massachusetts, have invented new and useful Improvements in Bookkeeping-Machines, of which the following is a specification.

This invention relates more particularly to bookkeeping machines, especially machines of the order of typewriting machines having attachments for tabulating, computing, etc. It is applicable not only to machines in which the account sheet on which the writing is done is mounted on a carriage that moves past the printing point, as in ordinary letter writing, but also to other types of machine, including those in which the printing mechanism is on the carriage, and "book typewriters."

It is herein described as it may be applied to a bookkeeping machine of a certain well known style having a movable carriage for the account sheet, means for writing with a step by step escapement, a series of "column stops" which can be adjusted according to the locations of the columns wherein figures are to be written on the account sheet, and a tabulating device by which the carriage can be brought to rest at a selected distance from the decimal point position. The type of column stop device herein used for illustration is one having means by which any desired number of lugs constituting the so-called "column stops" can be fixed in positions on the carriage, chosen according to the positions where the carriage is to stop for columns, with faces one behind the other in a straight line parallel to the direction of travel of the carriage, so that a lug on the frame holding the printing mechanism, stationed beside their line of travel and projected into it, will engage whichever of them comes next. And the particular type of decimal tabulating mechanism illustrated is one in which a number of such stationary lugs are grouped together in adjacent letter spaces, one for each decimal position in which it may possibly be desired to stop the carriage within any column whose location is determined by a column stop. While the description of the invention herein given is made specific to one particular type of machine, for illustration, and for conciseness, it must be remembered that there may be

many other embodiments of the invention, in forms suitable for other types of machine or for other details.

Tabulating devices commonly in use are supplied with means for releasing the ordinary step by step single space escapement used for writing, so that the carriage runs free of it and the operator upon finishing writing in one column can shift the printing point directly to the next one. In such cases the carriage travels under propulsion of its ordinary spring movement, except as restrained by its governor, if there be a governor; but where a machine is equipped with column stops for several different kinds of account sheets, having columns at different locations, or where different kinds of entries are to be made on the same account sheet, it will ordinarily happen that the desired stop positions are not the same for each sheet, or for each entry, yet the machine must stop at each column having a column stop, because it lacks the human intelligence to know which is wanted. Consequently the operator has to work the carriage along by stages to the desired column, stopping at every place where there is a column on the sheet or on any other sheet for which the machine is set, and pressing a tabulating key afresh to start the carriage along to the next column stop after each false stop. This involves a wasteful stress on the mechanism and upon the operator, both physically and nervously, and also a fruitless consumption of time. There is also the danger that the operator may write in a wrong column through a mistake of bookkeeping. It is among the objects of the present invention to eliminate these disadvantages by automatic operation of the mechanism; so that, when the operator is ready, the carriage proceeds directly until the lug engages whatever particular column stop corresponds to the next column in which something should be written, according to the particular kind of entry which is being made. To this end the invention employs a means for preventing writing in undesired columns, by running past them; and means whereby the stationary lug and all column stops which might be in engagement with it are prevented from being so engaged unless they are the particular ones which will stop the carriage with the printing point at the desired columns.

The invention relates more particularly to

automatically controlled mechanism, such that, when the operator actuates the tabulating device as a means of starting the carriage and predetermining the decimal position in which it shall come to rest, the controller causes the lug which is to engage the column stop to be thrown out of column stop engaging position, and back into it, as the carriage moves along. Thus the columns 5 in which writing may not be done because the carriage is running past are predetermined, according as the controller is designed, and those in which writing may be done because it is at rest. The objects of the invention 10 are accomplished by providing means by which a controller of variable design, according to what is proper for various kinds of entries, deprives the lug-projecting-mechanism of capacity for working while the 15 printing point is passing columns wherein no stop ought to be made, and restores its power, and, if necessary, operates it, when the column next in order is one wherein a stop is predetermined by the controller. 20 25 The invention may have many different embodiments within the meaning of the appended claims. It is intended to have the patent cover by suitable expression in these claims whatever features of patentable novelty the present applicant has contributed to the disclosure here made.

In the accompanying drawings:

Figure 1 is a side elevation showing an embodiment of the invention in medial section, with various parts of the typewriting machine broken away or omitted, as normally at rest in "working" position; 30 Fig. 2 is a plan of the same, with parts broken away or omitted; 40 Fig. 3 is a front elevation of a detail of the same in section about on the line 3—3 of Fig. 1; 45 Fig. 4 is a side elevation of part of the same in "non-working" position on a larger scale;

Fig. 5 is the same as Fig. 4, but in "working" position and as actuated;

Fig. 6 is a front elevation of a detail, the swinging frame; and

Fig. 7 is a plan of another detail.

Referring to the drawings, 10 indicates the platen on which one or more account sheets 11 are assembled and are held, in the position indicated by the double lines, by 55 any customary or suitable appliance. It is assumed that when more than one sheet is used all are arranged with the columns of the several sheets in registry with each other. The writing keys are marked 12, and the 60 spacing bar 13. Their connections and the type and type action are omitted for clearness. The keys 14 operate the tabulating mechanism seen at the left in Figs. 1 and 2, which may be of any suitable type, and 65 which is here illustrated as being of a well known style. In this, when the operator depresses one of the tabulating keys 14 the rear end of its lever 15 rises, thrusting upward one of a bank of flat reeds 16, so that it projects upward to the dotted line position at the upper left hand corner of Fig. 1, where it is in line to engage whichever comes next of the "column stops" 17 on the rear bar 18 of the carriage. The reeds 16 are set vertically at distances apart equal to adjacent letter spaces, with their broad sides toward the direction from which the column stops approach them, and adapted to engage such when projected into their line of travel. One such broad side is seen in Fig. 1, and the group of their tops is seen in Fig. 2. The column stops may be of any suitable construction, the style illustrated being seen best in Figs. 1, 2, 3 and 4, where the rear bar 18 of the carriage is represented as having a rack on its rear face, capable of holding each column stops 17 rigidly wherever it is placed thereon. In the construction and use of the machine of the invention it is contemplated that one of these stops 17 shall 70 be set for each columnar position that occurs, in which it may be desired to write on any of the account sheets for which the machine is set up. Where there are a variety of kinds of entries to be made in the account, each kind of entry occupying a combination of columns different from the combination of columns occupied by other entries, as for example one kind having parts in date, number, item, debit and balance 80 columns while another kind uses date, number, item, credit and balance columns, there will be one or more column stops positioned so as to stop the carriage at a column that is not required for the particular entry which 90 is to be made. It is one purpose of the invention to provide means by which such temporarily unwanted column stops shall not operate to stop the carriage. The apparatus for doing this embodies an automatic 95 device including a column key, and a controller therefor. The term "column key" is used by analogy to the present so-called letter or other character writing keys and to the tabulating keys, and refers to the part 100 of the mechanism which is actuated in selecting the column in which the tabulation and writing shall occur. Such actuation is automatically effected by the controller. One controller 20 is provided for each kind 110 of entry that is to be made according to the particular combination of columns that each kind requires, and these various controllers, all of which are marked 20, but which operate only as alternatives for each other are 115 preferably so mounted that any one can be quickly put into place. In the drawing eight such controllers are represented, mounted on an octagonal support 19 which is rotatable on its axis like a cylinder to 125 130

move any one of them into working position. The controllers illustrated are in the style of cams, having elevations 21 and depressions 22 co-acting with a cam roller 23 which constitutes the end of the column key. As represented in Fig. 1 the column key consists of this cam roller and its connected system of linkage. A pair of parallel pieces 24 rigidly supported on the frame of the machine and extending toward the front have two separated pivots from which links 25 and 27 rise to pivotal connection with a parallel but movable piece, 28, the front end of which, rising still higher, carries the cam roller 23. The pieces 24 may preferably be curved upward so as to constitute lateral supports for the cam holding part 28. The group is preferably located in the center of the machine closely forward of that part of the frame which has the writing scale 30. The octagonal holder 19 for the controllers 20 is represented as being just above the said scale, occupying the position of the scale as closely as may be. This location of parts is however largely a matter of convenience and may be arranged otherwise at pleasure. The piece 28 which supports the cam roller 23 is capable of moving with it toward or from the body of the machine, that is to the right or left as portrayed in Fig. 1, swinging with the tops of the links 25 and 27. Rigidly connected with the inner link 25 is an arm 31 projecting inward a short distance, the arm and link together constituting practically a bell crank. A spring 32 tends always to draw the arm 31 downward; and a vertical rod 34 is attached to the arm by a pivot 33, so that when the cam wheel 23 is opposite a depression in a controller 20 it moves inward, toward the left of Fig. 1, the bell crank link 25 swings to the left, and arm 31 and rod 34 swing downward, this whole movement of the column key being actuated by the spring 32. The lower end of the rod 34 is attached to and depresses the forward end of a lever 35, extending from front to back at the very bottom of the machine, fulcrumed under the middle of the machine at 36, and having a rear end provided with an upstanding head 37, containing a slot 38 obliquely cut therein and adapted to act as a cam on a horizontal rod 39 which passes transversely through it and through the group of reeds 16, *i. e.* extending in the direction of movement of the carriage. Depression of the rod 34 elevates the head 37, during which movement the underwall of the slot 38 forces the rod 39 backward, and so forces the entire bank of reeds 16 backward far enough for their lower ends to be behind and out of engagement with their respective actuating levers 15, as illustrated in Fig. 4. As they go back any one of them which has been lifted into stop engaging position by its lever 15 drops down, leaving all

stops 17 free to pass. A part of the mechanism connected with this is a pivoted frame 40, of which the rod 39 is a part swinging on a fulcrum at 41 a little above the head 37. The shape of this frame 40 is seen in front elevation in Fig. 6. Each reed 16 has a notch 41' in its front edge capable of receiving the pivot rod 41 as seen in Fig. 1. This rod may serve as a confining barrier which prevents the reeds from moving too far toward the front of the machine. However, this function is preferably served by the lower rod 39 of the frame which penetrates every reed 16, passing through and loosely fitting a vertical slot 39' in each so that its swinging swings them all and limits their throw to front or to rear. These slots 39' are long enough for each individual reed to execute its vertical motion, incidental to being elevated to its position for engaging the column stops, or falling back therefrom, without hindrance by the rod 39. The upright or forward position illustrated in Fig. 1 with the reeds over their levers 15, is herein called the "working" position; and the tilted position of Fig. 4 with the lower parts of the reeds behind their actuating levers 15, the "non-working" position. Springs 43 are provided, one for each reed, tending to hold each down; and the reeds are guided or held in place by being inclosed between various adjacent parts. Thus, their tops are guided between two plates 44, provided with edges serrated so as to fit the beveled edges of the tops of the reeds. This serration and beveling provides a strong support for resisting the shock when engagement of the lugs occurs. The reeds are prevented from swinging too far to the rear by cross-bar 46 in the frame of the machine, at a moderate elevation and by another 47 at the bottom. They are individually recessed at their back edges or are narrow enough, so that they can swing backward from the position of Fig. 1 to that of Fig. 4, the bar 46 then entering the recess 46' and the said bar 47 entering the terminal recess 47'; and these recesses 46' and 47' are long enough to permit of vertical movement of a reed 16 for the distance requisite to reach its elevated stop-engaging position. On their edges toward the front of the machine the reeds 16 have notches 48' in the middle part of their height, for engagement of a universal bar or plate 48 projecting as an arm from a rock shaft 49. The edge of each reed 16 which is toward the front of the machine is beveled at the bottom, as at 42', the angle illustrated in the drawing being about 45°. There is however a short horizontal foot 43' at the bottom, back of this bevel; and this shaping of the faces at the bottom forward corner of the reed is adapted to co-operate with the adjacent faces at the rear upper corner of the tabulating lever 15. Said 130

lever has a correspondingly beveled portion 42, a horizontal portion or table 43" on which the reed foot 43' rests when the reed is in working position, and a beveled portion 42" extending thence farther to the rear and downward on which the reed surface 42' can slide, as hereinafter more fully explained, when the reed 16 resting in working position on the table 43" of lever 15 and, 10 having been elevated by a depression of one of the tabulating keys 14, is pushed off of the resting place by a backward swinging of the transversely extending rod 39 into non-working position. Such swinging of all of 15 the reeds is effected by the cam slot 38 on the head 37 of the column key lever 35 whenever the cam roll 23 falls into a depression 22 in the controller 20. When thus moved backward off of their tables 43" each reed 20 falls as far as its confining guides, or the rod 39, permit; and these are so arranged that any reed 16 which has been elevated into column-stop-engaging position, as shown 25 in Fig. 5, sinks until its top end is below the line of travel of the column stops, *e. g.* till it is flush with the plates 44, thus removing its lug from column-stop-engaging position notwithstanding that the particular tabulating lever 15 that raised it remains 30 elevated. The other reeds 16, which were not at the time raised to the position in which the single one is illustrated in Fig. 5, simply move backward, all resting on the swinging transverse rod 39. When that rod 35 39 swings toward the front of the machine, to the right in Fig. 4, all of the reeds 16 move back into engagement with their respective operating levers 15, and incidentally that one reed which was raised, as in 40 Fig. 5, is again raised, till it rests on its raised lever 15 by the cam action of the beveled edge face 42' sliding up on the beveled end face 42" of its lever 15, assuming that the operator has continued to hold down the 45 particular tabulating key 14 which holds up the rear end of its particular lever 15. This puts the top end of that reed into position as a lug to engage the column stop which is then next in order. The other reeds 16 50 merely return to positions over the rear ends of their respective levers 15, at their lower level, their tops remaining flush with the tops of the plates 44.

The rock shaft 49 is turned whenever one 55 of the reeds 16 is raised because its arm 48 is arranged as a universal bar to be engaged by any reed that is raised. This shaft carries a collar 61 having an arm from which a rod 62 extends to an arm on a collar 63 on an 60 upper rock shaft 64, which as represented is located just in front of the upper part of the bank of reeds, being journaled there in two bosses which project from the frame of the machine. This upper rock shaft carries 65 an arm in the form of a tubular projection

65 extending toward the front of the machine and there supporting a pinion 66 which engages a rack on the underside of the carriage bar 67. This is the customary bar which, in a typewriting machine, extends along the carriage for the full distance of its travel and a little more, and during ordinary writing is in engagement with the pinion 68 of a step by step letter space escapement device 69, operated by the writing keys 12 or spacing bar 13. The escapement may be of any suitable type and is shown herein somewhat diagrammatically. The carriage bar 67 is mounted so that it can be lifted out of its engagement with the pinion 68, in which case the escapement is released and the carriage can move forward freely, so far as it is concerned, but as soon as the bar descends the escapement becomes again engaged. In the present case, means 80 is provided for thus lifting the carriage bar 67 and so releasing the escapement whenever one of the tabulating keys 14 is depressed, thus letting the carriage proceed freely until it is arrested by engagement of 85 one of the stops 17. The device for thus lifting the carriage bar 67 is the rock shaft 64 and the tubular projection 65 therefrom with pinion 66. In a tabulating machine not equipped with the present invention, 90 when any one of the tabulating keys 14 is depressed its corresponding reed 16 is raised, the universal bar 48 being lifted and the rock shaft 49 turned; and this motion, communicated through link 62, turns the 100 upper rock shaft 64 so as to lift the pinion 66. This pinion, being constantly in engagement with the rack of the carriage bar 67, lifts that bar high enough to release it from engagement with the escapement pinion 68. Incidentally the said tubular projection 65 and its pinion 66 may be utilized to provide a frictional governor, to control the speed with which the carriage moves when released from the escapement; but as 105 this construction forms no part of the invention it is not necessary to describe it further, and it may be understood that a frictional governor is embodied within the tubular shell 65, operated by a shaft therein on 110 which the pinion 66 is keyed. Also it will be understood that the machine has any suitable or customary spring for propelling it along the line of writing whenever the escapement is released, or permits it to go, but 115 such is not illustrated. Inasmuch as the escapement release as above described is brought about through the elevation of one of the reeds 16, and that reed, in a machine equipped with the present invention, is liable to be dropped to a non-stop position, in which case the universal bar 48 might fall, permitting through its connections the carriage bar 67 to reengage the escapement, the invention comprises means preventing such 120 125 130

reengagement. To this end an auxiliary universal bar or plate 55 is employed, acting as a strut between the inner ends of the series of tabulating levers 15 and the arm part 5 of the universal bar 48. Fig. 3 shows this in front elevation. There, as also in Fig. 5, it is seen to be liftable by any one of the levers 15, but it is provided with a slot 60 within which the lever 35 can rise without lifting it. The connection of its upper end to bar 48 is made in any suitable manner, the means illustrated consisting of the provision of two holes 57 in the latter through which a pair of prongs 56 rise from the universal bar 55. A further feature in this connection is the upward extension of one side 51 of the swinging frame 40, as clearly seen in Figs. 4 and 6. This extends far enough to engage as a latch behind the universal bar 48 which 20 acts as a keeper for it when not lifted, and thus the frame 51 is locked in its upright position, corresponding to the working position of the reeds 16. Thereby they are securely prevented from moving into and out 25 of working position with the progress of the carriage during ordinary writing when this part of the mechanism is not desired to be in use, and are held likewise during the return movement of the carriage. When this 30 frame is thus latched the cam roll 23 of the column key is in consequence prevented from entering the depressions of the cam controller 20. Hence the column selecting mechanism is kept out of action except when 35 one of the tabulating keys is depressed. This applies particularly during all return movements of the carriage, and during all ordinary writing, and in the latter case it permits the operator to write beyond the 40 confines of any column at will, regardless of the column key, and automatic controller, without setting the column selecting mechanism into action. The extension 51 also acts as a keeper for the bar 48 as a latch, to 45 hold the bar 48 up when once it has been raised, being of such length and width that its upper end engages under that bar when the frame 51 is tipped, thus holding the carriage bar 67 out of engagement with the 50 escapement so long as a depression in the controller 20 continues, notwithstanding that the tabulating key depressed by the operator may be in the meantime released. In this case the carriage will come to rest 55 when the escapement is returned to engagement.

The engagement of the part 51 of the swinging frame under the raised universal bar 48 also aids the return of the selected reed 16 to its place, for stopping the carriage, because the stout spring that tends to keep the bar 48 down is held by the keeper effect of the part 51 and does not have to be overcome by the cam sliding at 42, 42'.

65 The operation of the mechanism, there-

fore, is that, when a controller is in place corresponding to the kind of entry that is being made, the operator, in order to proceed from one column to the next which is proper for that particular entry has only 70 to depress the tabulator key 14 corresponding to the particular decimal place in which she wishes next to write. This starts the carriage along by lifting the carriage bar 67 and so letting the ordinary spring propulsion act without restraint by the escapement to move it at whatever rate the governor 65 permits. If any column stops that are not wanted intervene they are passed without being engaged, for the particular reed 16 that was raised by the tabulating key 14 is put out of action by the column key, so long as it is opposite a depression 22 of the controller. But when an elevation 21 thereof is reached, the head 37 85 is thrown down and the reeds 16 returned to working position, and the one for the particular selected decimal position is thus elevated into position to engage the next 90 column stop.

As has been previously herein stated, the invention may be embodied in many different forms, for example, the lug is not necessarily the movable member of the stopping device, as distinguished from the column stop bar; and the column stop bar is not necessarily on the carriage. While the controller illustrated is a cam, which also serves to actuate the column key, deriving its power from the main spring which propels the carriage, the controller is not necessarily a cam, and the force for actuating the column key does not necessarily emanate from the carriage or its spring, or pass through the controller, although obviously 100 whatever force there be for operating the column key is controlled by the controller according to the position in which the carriage is with respect to the writing line. The tabulating mechanism may be of any 105 suitable type. The number of lugs may be raised and even reduced to one, for some purposes; and the method of setting and removing the lug may vary, as well as the method of putting it out of working condition and into such condition; and the interlocking or latch features of the invention might be used in connection with some other kind of a column selecting device in which column stops were dispensed with; and 110 other variations may be made within the scope of the appended claims, or of some of them.

I claim as my invention—

1. Writing mechanism having a carriage, 125 with escapement and release; a column stop device; and actuating means for working the latter and the release; combined with a controller normally fixed in controlling position during operation of the machine and 130

connections whereby the said stop device works only as permitted by the controller.

2. Writing mechanism having a carriage with escapement and release; column stops, and means capable of engaging them; and actuating means for working the release and setting the parts so that said stops and means are in position for mutual engagement; combined with a controller normally fixed in controlling position during operation of the machine and connections controlling the working of said setting automatically according to the position of the carriage.

15 3. Writing mechanism having a carriage with escapement and release; a column stop device; and actuating means for working the latter and the release; combined with a controller normally fixed in controlling position during operation of the machine and connections including means for rendering the stop device non-working, the said controller being adapted to actuate the last mentioned means as the carriage moves along.

30 4. Writing mechanism having a carriage with escapement and release; a column stop device; and actuating means for working the latter and the release; combined with a controller normally fixed in controlling position during operation of the machine having a cam face and connections including means for rendering the stop device non-working, the said cam being adapted to actuate the last mentioned means as the carriage moves along.

45 5. Writing mechanism having a carriage with escapement and release; a column stop device; and actuating means for working the latter and the release; combined with a controller having a cam face and connections including means for rendering the stop device non-working, the said cam being adapted to actuate the last mentioned means as the carriage moves along, and having elevations corresponding to the carriage positions where the stop device is in working condition.

50 6. Writing mechanism having a carriage with escapement and release; a column stop device; and actuating means for working the latter and the release; combined with a controller having a cam face and connections including means for rendering the stop device non-working, the said cam being adapted to actuate the last mentioned means as the carriage moves along, and having elevations corresponding to the carriage positions where the stop device is in working condition; and a latch holding the said connections in their positions which correspond to the cam elevations, adapted to be unlatched by said actuating means for working the column stop device.

65 7. Writing mechanism having a carriage

with escapement and release; a column stop device, and actuating means for working the latter and the release; combined with a controller automatically controlling the said stop device and having a latch co-operating with and adapted to be released by the means for working the escapement release and to be held by it when it is not positioned to release the escapement, and the connections from the controller to the latch being adapted to be held inactive by the latch while the latch is so held.

8. Writing mechanism having a carriage with escapement and release and means to actuate the escapement release; column stops and means capable of engaging them comprising a lug, and a lever adapted to throw it into and out of stop engaging position; combined with a controller and means connected therewith for putting the said lug out of and into working arrangement notwithstanding it has been thrown into stop engaging position by said lever; there being a part of the last mentioned means constituting a latch adapted to engage a part of said throwing means whereby the putting of the lug out of working arrangement is prevented until the said means for throwing the lug is moved.

9. Writing mechanism having a carriage with escapement and release; column stops and means capable of engaging them comprising a lug and a lever adapted to throw it into and out of stop engaging position; and means to actuate the escapement release; combined with a cam extending in the direction of the writing line; a movable element controlled by the cam for putting the said lug out of and into working arrangement, adapted to engage a movable part of said lug throwing means, said movable part constituting a keeper for said movable element, barring its movement until the said means for throwing the lug is actuated.

10. Writing mechanism having a carriage with escapement and release; a column stop device; an operating key; separate trains of mechanism from it to the column stop device and to the escapement release; and a device for rendering the column stop device non-working, connected with the said train of mechanism leading to it, but not with said train of mechanism to the escapement release, combined with a controller and connections controlling said device for rendering the stop device non-working.

11. Writing mechanism having a carriage with escapement and release; column stops and means capable of engaging them comprising a lug and a lever adapted to throw it into and out of stop engaging position; means to actuate the escapement release combined with means independent of the lug throwing device for withdrawing the lug from the stop engaging position and

restoring it thereto; and a controller and connections adapted to actuate said independent means.

12. Writing mechanism having a carriage with escapement and release; a column stop device; a tabulating device for working the stop device and said release; combined with a controller and connections controlling the working of said stop device whereby it works only as permitted by the controller, thereby stopping the carriage at a selected tabulating position within a column predetermined by the controller.

13. Writing mechanism having a carriage with escapement and release; column stops and multiple means capable of engaging them comprising a series of lugs arranged at distances apart corresponding to adjacent letter spaces; means adapted to throw any selected one of them into and out of stop engaging position, and means to actuate the escapement release; combined with means independent of the lug throwing device for withdrawing a lug from its stop engaging position and restoring it thereto; and a controller and connections adapted to actuate said independent means.

14. Writing mechanism having a carriage with escapement and release; column stops and multiple means capable of engaging them comprising a series of lugs arranged at distances apart corresponding to adjacent letter spaces; means adapted to throw any selected one of them into and out of stop engaging position, and means to actuate the escapement release; combined with means independent of the lug throwing device for withdrawing a lug from its stop engaging position and restoring it thereto; and a controller and connections adapted to actuate said independent means; there being in said lug throwing and release actuating means separate levers and operating keys for actuating said separate lugs, and a universal bar, actuated by each lever and actuating the escapement release notwithstanding the lug actuated by such lever is so withdrawn.

15. Writing mechanism having a carriage with escapement and release and means to actuate the release; column stops and means capable of engaging them comprising a lug and a lever adapted to throw it into stop-engaging position and to permit its retraction therefrom; the lug being at one end of a reed held vertically and the other end of the reed when in working position being in the path of movement of said lever; and the reed being mounted so that it can move out of the path of movement of the lever; combined with means for moving the reed out of and into said path of the lever, and a controller controlling said reed movement.

16. Writing mechanism having a carriage with escapement and release and means to actuate the release; column stops and means

capable of engaging them comprising a lug and a lever adapted to throw it into stop-engaging position and to permit its retraction therefrom; the lug being at one end of a reed held vertically and the other end of the reed when in working position being in the path of movement of said lever; and the reed being mounted so that it can move out of the path of movement of the lever; combined with a lever having a cam engaging said reed, and adapted to move the reed into and out of the path of said first mentioned lever; and a controller automatically controlling said cam lever.

17. Writing mechanism having a carriage with escapement and release; column stops and means capable of engaging them, comprising a lug and means tending to retract the lug from stop-engaging position, and a lever for throwing it into stop-engaging position; a controller and connections therefrom to the lug to disconnect it from the lever; and means adapted to maintain connection from the lever to said escapement release independent of the lever's connection to the lug.

18. Writing mechanism having a carriage with escapement and release; column stops and multiply means capable of engaging them, comprising a series of lugs arranged at distances apart corresponding to adjacent letter spaces; means adapted to throw any selected one of them into and out of stop engaging position, and means, actuated by the throw-in means for any one of said lugs, to actuate the escapement release, and to hold it independently whether or not the lug remains in stop-engaging position; combined with means independent of the lug throwing device and applicable to all of the lugs for withdrawing any of them from its stop-engaging position and restoring it thereto; and a controller acting automatically as the carriage progresses, and connections adapted to actuate said withdrawing and restoring means.

19. Writing mechanism having a carriage with escapement and release; column stops and means capable of engaging them, comprising a lug and connections adapted to throw the lug into stop engaging position, means tending to retract the lug from stop engaging position; a controller automatically controlling said lug connection; a connection from the said lug lever to operate the escapement release; and means whereby the said connection to escapement release prevents working of said lug disconnecting means except when in position for releasing the escapement.

20. Writing mechanism having a carriage with escapement and release; column stops and means capable of engaging them comprising a multiplicity of lugs; levers for throwing them separately into stop engag-

ing position; means for actuating the escapement release and a universal bar connecting it to all of said levers whereby it is actuated by any one of them; a universal bar 5 connected with said lugs and moving them all into and out of connection with said levers; and a controller automatically controlling such movement; the two said universal bars coöperating with each other, the 10 lug bar having a part acting as a latch and the escapement bar as its keeper when in position for release of said escapement.

21. Writing mechanism having a carriage with escapement and release; column stops 15 and means capable of engaging them comprising a multiplicity of lugs; levers for throwing them separately into stop engaging position; means for actuating the escapement release and a universal bar connecting 20 it to all of said levers whereby it is actuated by any one of them; a universal bar connected with said lugs and moving them all into and out of connection with said levers; and a controller automatically controlling 25 such movement; the two said universal bars coöperating with each other, the lug bar having a part acting as a latch and the escapement bar as its keeper when in position for release of said escapement and the said 30 latch part of the lug bar constituting a keeper for the escapement bar to prevent its return to position for reengagement of the escapement while the lug bar is in position disconnecting the lugs.

22. Writing mechanism having a carriage with escapement and release, and means to actuate the release; column stops and a lug capable of engaging them, the lug being at one end of a reed held vertically, means to 40 lift the lug vertically into stop engaging position, the reed being mounted so that it can move laterally from said lifting means; means for so moving the reed, including a controller automatically controlling such 45 movement and a lever having one end movable beside said reed and having a cam slot therein adapted to move a part engaged in the cam slot from and to said lifting means; and a bar, engaged in said slot and in a 50 vertical slot in said reed, whereby the reed can fall when thus freed from said lifting means and while said bar remains in said cam slot.

23. Writing mechanism having a carriage 55 with escapement and release; column stops and multiple means capable of engaging them comprising a series of lugs arranged at distances apart corresponding to adjacent letter spaces, said lugs being the top 60 ends of vertical reeds and having at their lower ends vertical slots arranged to register together; means holding the reeds loosely in position; a movable bar traversing them through said slots; a lever extending between the reeds and engaging

said bar and adapted to throw it and thereby said reeds toward front or rear within their said holding means; a controller automatically controlling said lever; and hand operated means for lifting any selected individual of said reeds when forward; thereby causing its upper end to engage said column stops.

24. Writing mechanism having a carriage with escapement and release; column stops 75 and multiple means capable of engaging them comprising a series of lugs arranged at distances apart corresponding to adjacent letter spaces, said lugs being the top ends of vertical reeds and having at their 80 lower ends vertical slots arranged to register together; means holding the reeds loosely in position; a movable bar traversing them through said slots; a lever extending between the reeds and engaging said bar 85 and adapted to throw it and thereby said reeds toward front or rear within their said holding means; a controller automatically controlling said lever; and hand operated means for lifting any selected individual of 90 said reeds when forward; thereby causing its upper end to engage said column stops; and a swinging frame of which said traverse bar is a part, pivoted on the frame of the machine and supporting said traverse 95 bar.

25. Writing mechanism having a carriage with escapement and release; column stops 100 and multiple means capable of engaging them comprising a series of lugs arranged at distances apart corresponding to adjacent letter spaces, said lugs being the top ends of vertical reeds and having at their 105 lower ends vertical slots arranged to register together; means holding the reeds loosely in position; a movable bar traversing them through said slots; a lever extending between the reeds and engaging said bar and adapted to throw it and thereby said reeds toward front or rear within 110 their said holding means; a controller automatically controlling said lever; and hand operated means for lifting any selected individual of said reeds when forward; thereby causing its upper end to engage said 115 column stops; and a swinging frame of which said traverse bar is a part, pivoted on the frame of the machine and supporting said traverse bar, and having a latch part; there being an element actuated by said lug 120 lifting means, which when so actuated permits said latch part and frame to swing, but when not actuated bars such swinging.

26. Writing mechanism having a carriage with escapement and release; column stops 125 and means capable of engaging them, comprising a multiplicity of lugs; a multiplicity of reeds, extending vertically, whose upper terminals are the said lugs; means confining the upper terminals of said reeds 130

- to vertical movement and permitting movement of their lower portions laterally to the front or rear as well as vertically; operating means engaging their lower portions, adapted to lift them into stop engaging position when forward, and to permit them to fall thence when backward; a controller, and means whereby it controls the movement of the bottom of said reeds 10 to front or rear.
27. Writing mechanism having a carriage with escapement and release; column stops and means capable of engaging them, comprising a multiplicity of lugs; a multiplicity 15 of reeds, extending vertically, whose upper terminals are the said lugs; means confining the upper terminals of said reeds to vertical movement and permitting movement of their lower portions laterally to the front 20 or rear as well as vertically; operating means engaging their lower portions, adapted to lift them into stop engaging position when forward, and to permit them to fall thence when backward; a controller, and 25 means whereby it controls the movement of the bottom of said reeds to front or rear, the said operating means for lifting reeds having cam surface connection thereto, whereby the reeds descend on moving backward and rise on being moved forward upon 30 said operating means.
28. Writing mechanism having a carriage with escapement and release; column stops and means capable of engaging them, comprising a multiplicity of lugs; a multiplicity 35 of reeds, extending vertically, whose upper terminals are the said lugs; means confining the upper terminals of said reeds to vertical movement and permitting movement of 40 their lower portions laterally to the front or rear as well as vertically; operating means engaging their lower portions, adapted to lift them into stop engaging position when forward, and to permit them to fall 45 thence when backward; a controller, and means whereby it controls the movement of the bottom of said reeds to front or rear and said operating means having parts which when operated rise adjacent to the 50 lower portions of the reeds; a strut resting upon all of them and lifted by any one of them; and a connection from said strut to said escapement release whereby the action of any one of said operating means releases 55 the carriage from the escapement.
29. Writing mechanism having a carriage with escapement and release; column stops and means capable of engaging them comprising a lug; and means to actuate the lug 60 to move it into and out of stop engaging position; combined with a controller and means connected therewith for putting the said lug out of and into working arrangement; a pivoted plate engaged with and 65 swinging with said lug between its working and non-working position; mechanism for actuating the escapement release, including another pivoted plate swinging with such actuation; the two said swinging plates being arranged with their arcs of movement 70 intersecting, each being a latch and each a keeper for the other.
30. Writing mechanism having a carriage with escapement and release and means to actuate the escapement release; column stops 75 and means capable of engaging them comprising a lug, and a lever adapted to throw it into and out of stop engaging position; combined with a controller and means connected therewith for putting the said lug 80 out of and into working arrangement notwithstanding it has been thrown into stop engaging position by said lever.
31. Writing mechanism having a carriage with escapement and release; a series of 85 column stops and a lug capable of engaging them; and means predeterminedly arranged and normally fixed in position during operation of the machine whereby the movement of the carriage along the writing line 90 controls the moving of the lug out of and into line for engaging one of said column stops.
32. Writing mechanism having a carriage with escapement and release; column stops 95 and a reed having a lug capable of engaging them; the engaged portions thereof being in line one behind another; actuating means for setting the lug in said line and working said release; the said actuating 100 means and reed being mutually adapted to be separated with the means standing unengaged in setting position by the reed while the lug remains unset and ready to be set; and a controller and connecting mechanism 105 whereby the movement of the carriage along the writing line transfers the reed from said separated into said engaging position as respects the actuating means, thereby setting the lug, at a point predetermined by said 110 controller.
33. Writing mechanism having a carriage with escapement and release; tabulating mechanism for actuating the release and causing the carriage to stop in a selected 115 position within a column, and a controller normally fixed in controlling position during operation of the machine, and connections whereby the tabulating mechanism is effective only at columns predetermined 120 thereby.
34. Writing mechanism having a carriage with escapement and release; column stops and lug mechanism capable of engaging them to stop the carriage; tabulating mechanism for setting the said lug mechanism and releasing the escapement; and controller mechanism rendering the said lug mechanism non-working except at positions predetermined by said controller. 125 130

35. Writing mechanism having a carriage with escapement and release; column stops and lug mechanism capable of engaging them to stop the carriage; tabulating mechanism for setting the said lug mechanism and releasing the escapement; and controller mechanism rendering the said lug mechanism non-working except at positions predetermined by said controller, there being an interlocking connection preventing operation of the controller mechanism when the tabulating mechanism is not actuated.
36. Writing mechanism having a carriage with escapement and release; tabulating

mechanism for actuating the release and 15 causing the carriage to stop in a selected position within a column; a controller and connections, whereby the tabulating mechanism is effective only at columns predetermined thereby; and a latch preventing the 20 actuation of said connections, except when the tabulating mechanism is actuated.

Signed by me at Boston, Mass., this twenty-eighth day of April 1917.

FERDINAND M. HOLMES.
